UNITED STATES PATENT OFFICE.

PAUL VOIKU, OF EAST YOUNGSTOWN, OHIO, ASSIGNOR OF ONE-HALF TO JOHN VATI,
OF NEW CASTLE, PENNSYLVANIA.

HAIR CLIPPER.

Application filed July 31, 1924. Serial No. 729,272.

To all whom it may concern:

Be it known that I, PAUL VOIKU, citizen of the United States, residing at East Youngstown, in the county of Mahoning and State of Ohio, have invented certain new and useful Improvements in Hair Clippers, of which the following is a specification.

This invention relates to hair-clippers, and has for its object the production of an electrically driven, but manually operated and guided, device for clipping hair from the human head.

Figure 1 of the drawings represents a top plan view. Figure 2 is an end view with the handle member partly broken away and in section to disclose the mechanism housed therein. Figure 3 is an end elevation with the casing removed. Figure 4 is a longitudinal sectional view of one end of the device. Figure 5 is a cross sectional view on line 5—5 Figure 6. Figure 6 is a front elevation with casing shown in section. Figure 7 is an outline of the teeth of the comb, showing the different widths of the teeth of the comb used as the operation progresses. Figure 8 is a sectional view on line 8—8 Figure 6.

Similar reference characters designate corresponding parts throughout the several figures of the drawings.

Referring to the drawings, 1—1 represent oppositely disposed head pieces, which, together with the shafts mounted therein as hereinafter specified, comprise what may be termed the frame-work of my device, and as the two ends of the device are in all respects duplicates, the specifications will be confined to one end and written in the singular number.

Rotatably mounted in the end piece 1 is the shaft 2. Rigidly attached to shaft 2, adjacent the inner face of the head piece 1, is the disk 3, to which are attached a plurality of cutting bars 4. Also rigidly attached to said shaft 2, outside of the head piece 1, is the grooved pulley *p*.

Also rotatably mounted in the head-piece 1 is the shaft 5, to which is rigidly attached the grooved wheel or pulley 6 disposed in the recess 7 formed in the head piece 1. Also mounted upon said shaft 5 is the retracting coil spring 8, having its free end secured to the cross-bar 9.

Rigidly secured to the outer face of head piece 1 is the forked bracket 10, each arm of which is provided with a central slot 11, within which is slidably mounted a head-block provided with a central opening which serves as a sliding journal for one end of the counter-shaft 12. Rigidly mounted upon said counter-shaft 12, and between the two arms of bracket 10, is the grooved pulley 13, while between the inner arm of bracket 10 and the end piece 1 is the gear wheel 14.

The counter-shaft 12 is driven by belt 6 running on pulleys *p* and 13. 15 represents a comb which is slidably secured to the lower face of the head-piece 1 by the grooved flange 16 attached to the end of the comb, and carrying the toothed rack 17 (Figure 3), and the complementary grooved bracket 18 attached to the end piece 1. Attached to the back 19 of the comb 15 is a small loop 20, to which is secured one end of a flexible band 21 which passes around the small idle pulley 22 and has its opposite end secured to the grooved wheel 6 carried by the rocker shaft 5, as hereinbefore explained.

23 represents the handle which is mounted upon the post 24 disposed in the loop 25 of the cross-bar 9, and secured to the frame by the oppositely disposed holding arms 26 and rivets 27.

Enclosed within the hollow of the handle (see Figure 2) is a wire loop 28 held normally in retracted position by coil spring 29. The outer end of this loop is bent downwardly adjacent the end of the handle (see 29a Figure 4), and then at substantially right angles, running longitudinally with the machine (see 30) beyond the outer face of the end piece 1, where it is again bent at substantially right angles, and extends across the outer face of the end piece 1 (see 31), and has its upper end attached to the counter-shaft 12 carrying the gear wheel 14. Firmly secured to the loop 28, and extending up through the slotted opening 32 in the handle, is the knob or button 33. The curved arm 34 attached to the handle is designed merely as a finger rest or support for the convenience and support of the operator.

As already suggested and outlined in Figure 7, various width comb teeth may be

used, the narrow one at the commencement, and increasing in width as the operation approaches the crown of the head.

It will be understood, of course, that shaft 5 2 is adapted to be driven by electricity through the medium of a flexible driving member attached to the shaft and leading to the source of power.

As a cover and protection for my device, 10 and for the purpose of holding hair-clippings, I use a metal casing 35 formed in two sections, embracing the entire device and held in position by end caps 36. A door 37, hinged as at 38, is provided for the purpose 15 of removing the clippings from the casing.

The operation of my device is as follows:

It is obvious that the comb 15 is held normally in an advanced position by the flexible band 21 attached to the pulley 6 rigidly 20 mounted upon the spring controlled rocker shaft 5. When the operator desires to retract the comb, he presses the button 33 forward, thus forcing the loop 28 outwardly from the handle, and causing the gear 14 25 mounted upon the counter-shaft 12 to engage the toothed rack 17 on the flange 16 attached to the comb, thus driving the comb in the opposite direction against the resistance of spring 8, and when the operator releases the 30 button 33, the gear 14 will become disengaged from the rack 17, after which the comb will be immediately drawn back to normal position by the band 21.

I claim:

35 1. In a device of the character described, a frame-work, a rotary cutting member mounted therein, means for driving said cutting member, a counter-shaft mounted upon said frame-work and carrying a gear 40 wheel, means for driving said counter-shaft, a comb slidably mounted upon said frame-work and provided with a transverse toothed rack adapted to be engaged by said gear wheel, means for engaging and disengaging said wheel and rack, and means for holding 45 said comb in normal position.

50 2. In a device of the character described, a frame-work, a rotary cutting member mounted therein and carrying a pulley, means for driving said cutting member, a counter-shaft mounted upon the end of said frame-work and carrying a pulley and a gear wheel, a belt running upon said two pulleys, a comb slidably mounted upon said 55 frame-work and provided with a transverse toothed rack adapted to be engaged by said gear wheel, means for engaging and disengaging

gaging said gear wheel and rack, and means for holding said comb in normal position.

60 3. In a device of the character described, a frame-work, a rotary cutting member mounted therein and carrying a pulley, means for driving said cutting member, a counter-shaft mounted upon the end of said frame-work and carrying a pulley and a gear wheel, a belt running upon said two pulleys, a comb slidably mounted upon said frame-work and provided with a transverse toothed rack adapted to be engaged by said gear wheel, means for engaging and disengaging 65 said wheel and rack, a spring controlled rocking shaft carrying a pulley, and a flexible connection between said pulley and said comb.

70 4. In a device of the character described, a frame-work, a rotary cutting member mounted therein, means for driving said cutting member, a counter-shaft slidably journaled upon the end of said frame-work and carrying a gear wheel, means for driving said counter-shaft, means for shifting its 75 slidable journals, a comb slidably mounted upon said frame-work and provided with a transverse toothed rack adapted to be engaged by said gear wheel, a spring controlled rocking shaft, and a flexible connection between said rocking shaft and said comb.

80 5. In a device of the character described, a frame-work, a rotary cutting member mounted therein, means for driving said cutting member, a counter-shaft slidably journaled upon the end of said frame-work and carrying a gear wheel, means for driving said counter-shaft, a comb slidably mounted upon said frame-work and provided with a transverse toothed rack adapted to be engaged by said gear wheel, a 85 spring controlled rocker shaft, a flexible connection between said rocker shaft and said comb, a handle member attached to said frame-work, and a spring controlled manually operated adjusting element partially housed within said handle member and having its outer end connected with said counter-shaft.

90 In testimony whereof I hereunto affix my signature in the presence of two witnesses.

PAUL VOIKU.
